(57) **CLAIM**

The ornamental design for a rugby jumper support grip, as shown and described.

DESCRIPTION

U.S. utility patent application Ser. No. 11/499,023.

U.S. utility patent application Ser. No. 11/800,356.

U.S. utility patent application Ser. No. 11/899,529.

FIG. 1 is a perspective view of a rugby jumper support grip, showing my new design;

FIG. 2 is a back view thereof;

FIG. 3 is a front view thereof;

FIG. 4 is a top view thereof;

FIG. 5 is a bottom view thereof;

FIG. 6 is a right view thereof; and,

FIG. 7 is a left view thereof.

My rugby jumper support grip is characterized as a cylindrical section, where the front is rounded, the back has a circular groove, and the ends are rounded and tapered.
